UNITED STATES PATENT OFFICE.

ROBERT H. COWDERY, OF CLEVELAND HEIGHTS, OHIO, ASSIGNOR TO THE AMERICAN FORK AND HOE COMPANY, OF CLEVELAND, OHIO, A CORPORATION OF OHIO.

MANUFACTURE OF FORKS.

1,279,660.

Specification of Letters Patent. Patented Sept. 24, 1918.

Application filed March 21, 1918. Serial No. 223,725.

To all whom it may concern:

Be it known that I, ROBERT H. COWDERY, a citizen of the United States, and a resident of Cleveland Heights, county of Cuyahoga, 5 and State of Ohio, have invented a new and useful Improvement in the Manufacture of Forks, of which the following is a specification, the principle of the invention being herein explained and the best mode in which 10 I have contemplated applying that principle, so as to distinguish it from other inventions.

The present invention, relating, as indicated to the manufacture of forks, is particularly concerned with an improved 15 method of forming blanks to be worked into heavy forks such as are commonly used in handling vegetables, ensilage, coal and coke, stone and other ballast materials and 20 similar articles. Such forms are commonly provided with eight or more tines of relatively large size.

At present forks of this character are made by first forming T-shaped blanks, the 25 projecting portion of the blank serving to form the shank or handle-entering member, and the other portion of the blank being notched at its center. After this notching operation the blank is formed into the required 30 number of teeth, each tooth being formed separately in a press. After these teeth are preliminarily formed by being stamped from the solid bar the bar has to be straightened and the tines are then rolled 35 in suitable rolling machines for the purpose. The objection to this method of producing forks is that it is slow and expensive, since the tines must be stamped out separately from the original T-shaped blank.

On the forks having eight or more tines, 40 it has heretofore been considered impossible to produce all of the tines in a single stamping operation since this relatively large number of tines cannot be formed on two sides 45 of the head as is customary in the stamping out of four and six-tine forks, in which half of the tines are formed on one side of the head and the other tines and the handle-receiving member on the other side. My 50 improved method provides a means for forming blanks in which all of the teeth can be formed in a single operation from a strip of stock with very little waste. To the accomplishment of the foregoing and re-

lated ends, said invention, then, consists 55 of the means hereinafter fully described and particularly pointed out in the claims.

The annexed drawing and the following description set forth in detail one method and one product exemplifying my invention, such disclosed procedure and product constituting, however, but one of various 60 applications of the principles of my invention.

In said annexed drawing:— 65

Figure 1 is a plan view of a strip or bar of stock on which the pattern of the blank is indicated; Fig. 2 is a view of one of the blanks after it is severed from the stock bar; Fig. 3 is a view of the blank after 70 straightening; and Fig. 4 is a view of the finished fork.

Referring now to Fig. 1, there is shown a rectangular strip 1 of metal of suitable thickness, from which the blanks are to be 75 stamped. It will be understood that the stamping of the blanks from this strip of stock can be performed in a suitable heavy press, and it is not thought necessary to illustrate either the press or the die members used therein as the general construction of each will be familiar to those skilled in the art from the description of the blanks. 80

In order to avoid waste two blanks are formed together from a single length of 85 stock, the blanks facing in opposite directions as they are cut from the bar and the tines of the two blanks being interposed within each other as will presently be described. The head 2 of the fork will be 90 formed for a portion of its length from one outer edge of the stock bar 1 and is then curved inwardly as at 3, this portion 3 being substantially at the center of the head strip. The head strip 2 then extends parallel with the outer edge of the strip 1 for a portion 4 of its length, and then again curves outwardly at 5 toward the edge of the bar. Projecting transversely of the stock bar 1 and inwardly from the head portion 2 are 95 tines 6, all of which are substantially the same size and shape, except the end tines 7 and 8, which are longer and slightly narrower than the intermediate tines, while the end tine 7 extends across the stock bar to 100 effect a severance of the formed blanks from the bar. The exact size and shape of the portions which are to be formed into the

105

tines is immaterial, as these tines are of course subsequently rolled to the proper size and cross section and are then cut off at the same length.

5 Projecting outwardly from the center of the head 2 at the point 3 is a strip 9, which is adapted to serve as the shank or handle entering member of the form, and this member 9, as indicated, extends along the edge 10 of the strip 1 and is of sufficient width to permit it to be subsequently formed into the desired shape, by suitable rolling.

The second blank is formed from the other side of the stock strip 1, opposite to and interlacing or interlocking with the tines 6, 7 and 8 of the first blank. The portions of this second blank are identical in their construction and in their size and location with the portions of the first blank, the tines of 20 the two being interposed between each other as indicated, so that when one blank is forced downwardly by means of a suitable die, the other blank is forced upwardly by a co-acting die, and the two are simultaneously severed from each other and from the strip of stock.

After being severed from the stock bar the blanks are straightened so that the portions of the head are in alinement, which automatically brings the tines into substantial parallelism which permits them to be rolled in the usual machine used for this purpose. After rolling they are cut off and the handle receiving member 9 being formed at any desired stage in the manufacture of the fork into a shank to engage a handle. The finished fork is illustrated in Fig. 4.

I have found that by forming the blanks in the manner described above there is no more waste than occurred in the usual method 40 of forming T-shaped blanks from a rectangular strip of metal and then notching the same to permit of the individual stamping out of the different tines. The amount of 45 material required in my improved method is therefore no greater than in previous methods, while the saving in labor and in the time of making the tines is considerable, although it necessitates a larger stamping 50 press than did the individual cutting of the tines in previous methods.

Other forms may be employed embodying the features of my invention instead of the one herein explained, change being made in

the form or construction, provided the elements stated by any of the following claims or the equivalent of such stated elements be employed, whether produced by my preferred method or by others embodying steps equivalent to those stated in the following 60 claims.

I therefore particularly point out and distinctly claim as my invention:—

1. In a method of forming fork blanks, the step which consists in punching out the opposed blanks from a single section of stock by forming the heads of such fork blanks along opposite sides of such section and with such head inclined away from the edges at one point and there forming shank members, with tine blanks extending transversely of such section from said head blanks and lying in interlaced relation with each other.

2. In a method of forming fork blanks, the step which consists in punching out the opposed blanks from a single section of stock by forming the heads of such fork blanks along opposite sides of such section and with such head inclined away from the edges at one point and there forming shank members with tine blanks extending transversely of such section from said head blanks and lying in interlaced relation to each other, with the end tine blanks extending across such stock 85 section.

3. As a new article of manufacture, a fork blank comprising a head formed of two parallel portions connected by a central portion lying at an obtuse angle to said parallel portions, and having a shank member extending from such central portion parallel with said parallel portions and tines extending from said head portion at right angles thereto.

4. In a method of forming fork blanks, the step which consists in punching out two opposed, tine interlaced blanks from a single section of stock by forming the heads of such fork blanks along opposite edges of such stock section with each head inclined away from the adjacent edge of said section at one point and with a shank member lying along such adjacent edge adjacent to the inclined portion of said head.

Signed by me, this 18th day of March, 1918.

ROBERT H. COWDERY.
